PNEUMATIC TOOL

Adolf J. Sgonina, St. Louis, Mo.

Application August 12, 1931, Serial No. 556,587

4 Claims. (Cl. 121—15)

This invention relates to pneumatic tools and more particularly to that class of pneumatic tool in which a rapid succession of hammer blows are provided for riveting, chipping and various other purposes.

The primary object of this invention is to improve the balance of a pneumatic tool, thereby greatly reducing vibrations.

Another object of this invention is to provide a pneumatic tool having two pistons synchronously operating in opposite directions.

Other and further objects and advantages of this invention will be disclosed in the specification, claims and drawings, in which:

15. Fig. 1 is a longitudinal section through the tool.
 Fig. 2 is a cross section along the line 2—2 in Fig. 1.
 Fig. 3 is an elevation of the lower end of the tool.
 20. Fig. 4 is a plan view of the tool, partly in section and taken at an angle of 90 degrees to the view in Fig. 1.
 Fig. 5 is a longitudinal section of the sectional part of the view in Fig. 4.

25. Fig. 6 is an elevation of the upper end of the tool.

The primary purpose of the invention, as above set forth is the production of a balanced pneumatic tool, in which two pistons 1 and 2, of equal mass, operate synchronously in opposite directions; that is to say, when piston 1 moves upwardly, piston 2 moves downwardly, hence it is obvious that the anvil 3 will receive two blows where heretofore with a single piston hammer it only received one blow. Therefore, the efficiency of the tool is approximately increased 100%.

For manufacturing reasons two identical cylinders 4 and 5 are provided and held in longitudinal axial alignment by through bolts 6 and 7 which are provided with the usual heavy springs 8 for absorbing vibration.

The adjacent ends of the cylinders 4 and 5 are separated by the members 9 and 10 which hermetically seal the ends of the cylinders. Between the members 9 and 10 and rotatably mounted is a ratchet wheel 11 provided with pawls in the usual manner, which are not shown nor claimed.

The anvil 3 is provided with three diameters, the largest of which, 12, is provided with a poly-
 50 angular bore 13 for receiving the working tool, and also provided with a shoulder 14 for receiving the blow of the piston 2. The second diameter 15 is provided with a plurality of spirally disposed key seats 16 which engage inwardly projecting members 17 protruding from the piston 2

in order to give the anvil rotary movement. The third diameter 18 extends through the ratchet wheel 11 and is, also, provided with a key seat 19 which engages a projection on the ratchet wheel to prevent reverse rotation. This feature 60 is neither shown nor claimed as it is usual construction.

The upper end of the cylinder 4 is hermetically closed by an end-piece 20 integral with which is an operating handle 21. The outer end 65 of the cylinder 5 is hermetically closed by the member 22, which is bored and finished to provide a guideway for the diameter 12 of the anvil 3.

Longitudinally disposed and rigidly affixed to 70 the cylinders 4 and 5, by means neither shown nor claimed, is a valve chamber designated as a whole as 23, made up of an external housing 24 and a plurality of parts to facilitate the manufacturing process and held together by bolts 25 75 and tap screws 26.

The valve chamber is longitudinally bored and finished to receive a reciprocable valve 27, which is also made of two identical parts to facilitate manufacturing. The operation of the valves 80 and the location of the ports are identical, hence only the upper one will be described, it being understood that the lower valve is a duplicate thereof. The valve consists of a hollow cylindrical portion 28, provided with an external annular ring 29. Longitudinally through the valve housing three bores are provided, 30 and 39 for the incoming air under high pressure, and 31 for the exhausting air. Leading to the extremities of the valves through the intake port 32 are 85 three additional bores through the valve housing, designated as 33. It is obvious that a plurality of bores are used to provide sufficient area in the smallest possible space, as all three of these bores 33 communicate with the interior or 90 hollow part of the valve, as shown at 34 in Fig. 1, and also in Fig. 4.

As shown in Fig. 2, two external exhaust ports 35 are provided, one in intermittent communication with the cylinder 4, and the other with 100 the cylinder 5. These ports are screw-threaded for the purpose of receiving an elbow nipple so as to turn the exhausting air downwardly or away from the operator.

With the exception of the external annular rings 29 and 29a which provide a greater superficial area than the superficial area of the valve contacted by the incoming air, the valve arrangement and operation are of the conventional and usual type used in pneumatic tools.

The operation of the tool is as follows:—Air under pressure from a compressor, tank or other source is admitted through port 32, thence through the longitudinal bores 33 into the lower hollow reciprocable valve (when the valves are in the position shown in Fig. 1), from which it flows through ports 38a at the closed end of the lower valve into the communicating channel 42 to the longitudinal bore 30, which terminates 10 in ports P at the extremities of the cylinders 4 and 5.

This flow of air into the cylinders will cause piston 1 to move down and strike the end-face of the anvil, 18, at the same time lifting piston 2 causing the anvil to rotate. The air displaced 15 on the under side of piston 1 and the upper side of piston 2 can flow away through ports Pa into the longitudinal bore 39, best shown in Fig. 5, and via the communicating channel 40 passes 20 the lower end of the upper valve into the annular chamber around the stems of the valves, thence through the ports 41 to the atmosphere.

The final position of the pistons is shown in Fig. 1. The exhaust ports 37 in cylinder 4 and 25 37a in cylinder 5 are now uncovered allowing the air in these cylinders to flow into these ports and press against the annular rings 29 and 29a of the valves, causing the valve to reciprocate. (In the case of cylinder 5, air flows into exhaust 30 port 37a communicating with the longitudinal bore 31, which in turn communicates with the port 37b). The combined area of these two annular rings is greater than the end area contacted by the incoming air, but it is to be particularly stressed that the area of either ring 35 singly is less than said contacted end area, so that air pressure against both rings together is absolutely necessary to actuate the valve in either direction, as by throwing the valve to the 40 right from its previous position shown in Fig. 1, and whereupon the lower valve portion will close off the incoming air at that side, but will permit of its entry through the corresponding port at the upper side. Thus, if either piston should 45 travel faster than the other to permit the incoming air to communicate with one of the annular rings or flanges, said faster moving piston would temporarily cease its travel and wait until the other piston had moved to the corresponding 50 point to permit communication with the other flange, and only then would there be sufficient pressure acting against the flanges to shift the valve. This synchronizes the movement of the pair of pistons, and prevents the possibility 55 of the tool being operated with but a single one of the pistons.

The exhaust air from the cylinders can now flow 60 past the annular rings 29 and 29a and out to the atmosphere through ports 35. The incoming air can now flow through the upper hollow reciprocable valve through ports 38 in its closed end and via communicating channel 40 to longitudinal bore 39, and thence to ports Pa communicating 65 with the adjoining ends of the cylinders 4 and 5.

The flow of air into these cylinders will cause 70 the piston 1 to be driven upward towards the

handle and piston 2 downward to strike the anvil on its face 14. During this operation the anvil will be held against rotation by pawls engaging the ratchet wheel 11, so that piston 2 will be forced to rotate. The air displaced above piston 1 and below piston 2 will flow via ports P into the longitudinal bore 30, thence via communicating channel 42 passed the upper end of the lower valve into the annular chamber around the valve stems to the atmosphere through ports 41. When the pistons reach their final positions, the exhaust ports 43 and 43a will be uncovered allowing the air from the cylinders to enter and press upon the annular rings 29 and 29a of the valves causing them to be thrown upward. This forms 80 a complete cycle which is repeated indefinitely 85 during the operation of the tool.

Having fully described my invention, what I claim as new and useful and desire to protect by Letters Patent is:—

1. A pneumatic tool of the kind described, comprising a cylinder; a pair of pistons reciprocally movable therein; air ports in said cylinder to either side of each of said pistons to alternately admit air thereto to actuate said pistons in mutually opposite directions; a valve controlling the admission of said air through said ports to said pistons; and means on said valve and operably controlled by said pistons together at a predetermined point of travel to actuate said valve. 100

2. A pneumatic tool of the class described, comprising a cylinder; a pair of pistons movable therein; a valve controlling the admission of air pressure to actuate said pistons in alternate directions; a pair of projections spaced apart on said valve; a port between each projection and said cylinder and uncovered at a predetermined point of travel of the pistons to admit air under pressure to both of said projections in unison to 110 actuate said valve. 115

3. A pneumatic tool of the kind described, comprising a cylinder having air intake ports; a pair of pistons movable therein; a valve controlling the admission of air to said pistons simultaneously through said ports and having end walls alternately exposed to the intake air pressure; means on said valve to control its movement; additional ports spaced from said first-mentioned ports and communicating between said cylinder and last-mentioned means, the effective area of 120 said last-mentioned means and the ends of said valve being so proportioned to require air pressure against both said means to operate said valve, to thereby synchronize the movement of the 125 pair of pistons. 130

4. A pneumatic tool of the class described, comprising a cylinder; a pair of pistons movable therein; air ports in said cylinder at the ends of each of said pistons to alternately admit air to the latter to actuate them in mutually opposite directions; a valve controlling the admission of air through said ports; and means movable with said valve and operably controlled by said pistons together at a predetermined point of their travel to actuate said valve. 135
